[57] CLAIM

The ornamental design for a pocket baseball game box,
as shown and described.

DESCRIPTION

FIG. 1 is a top plan view of a pocket baseball game box
showing my new design;

FIG. 2 is a left side elevational view thereof;

FIG. 3 is a right side elevational view thereof;

FIG. 4 is a front elevational view thereof; and

FIG. 5 is a bottom plan view thereof;

FIG. 6 is a perspective view thereof.

It is noted that the rear elevational view is a mirror
image of the front elevational view.

FIG. 1

FIG. 2

FIG. 3

FIG. 4

FIG. 5

FIG. 6
